UNITED STATES PATENT OFFICE

161,903

PORTABLE RADIO CABINET

Reuben C. Carlson, River Grove, Ill.

Application May 27, 1950, Serial No. 10,241

Term of patent 14 years

(Cl. D56—4)

To all whom it may concern:

Be it known that I, Reuben C. Carlson, a citizen of the United States, residing at River Grove, in the county of Cook, State of Illinois, have invented a new, original, and ornamental Design for a Portable Radio Cabinet, of which the following is a specification, reference being had to the accompanying drawings which form a part thereof.

Fig. 1 is a perspective view of the top, front and right-hand side of a portable radio cabinet showing my new design with the dial open; and

Fig. 2 is a view similar to Fig. 1 from the front and left-hand side showing the dial closed.

The dominant features of my design reside in the portion shown in full lines in the drawings.

The rear of the portable radio cabinet is plain.

I claim:

The ornamental design for a portable radio cabinet, as shown and described.

REUBEN C. CARLSON.
